COLLAPSIBLE CONTAINER

Victor Roy Scott, Frankton Junction,
New ZealandApplication November 8, 1934, Serial No. 752,017
In New Zealand August 11, 1934

8 Claims. (Cl. 217—12)

This invention relates to collapsible containers, or boxes which are formed of cardboard, wood, or the like.

The object of the present invention is to construct a container that will be inexpensive to manufacture, easy to assemble, light, and that will resist the entry of dust and air, such a container being particularly useful for the packing and export of butter, fruits and other perishable goods.

According to the present invention, the vertical side walls of the box and the horizontal walls which form the bottom and lid, have locking pieces attached to the inner sides of the walls parallel with the ends thereof. The ends of the box are formed by walls having locking pieces attached at their vertical ends to interact with the locking pieces attached to the ends of the vertical side walls. These locking pieces, when the box is assembled, form a rectangular interlocked frame for the ends of the box and support the sides and lock the end walls to the vertical side walls. The arrangement is such that when the three sides, that is, the bottom and the two vertical walls, are brought into relative assembled position, the end walls are simply slid into position, the locking pieces of the end walls sliding against the vertical locking pieces of the vertical walls and lock into the locking piece upon the bottom. The lid, upon being folded over, will permit its locking piece to lock into both the vertical locking pieces and thus complete the frame and secure the parts of the box firmly together.

The invention will be described in detail with the aid of the accompanying drawings, where-in:—

Figure 1 is a perspective view of the assembled box.

Figure 2 is a perspective view of the box with the lid opened.

Figure 3 is a perspective view of the box showing one end removed and the other end partially withdrawn.

Figure 4 is an end view of the frame with the walls in section.

Figures 5 and 6 are perspective views showing the construction of the corners.

Figure 7 is a perspective view showing how the corners of the frame fit together.

Figure 8 is a perspective view of a modification.

Figure 9 is a perspective view of a cardboard blank and ends with the cleats in position previous to folding into an assembled position.

Figures 9a and 9b are perspective views of the pertaining end walls.

Figure 10 is a plan of a cardboard blank.

Figure 11 is a fragmentary view of a slightly different form of blank.

Figure 12 is a view showing how a cleat is attached.

Figures 13A, 13B and 13C are views showing how the half-cleats are attached to the side walls and folded over.

Figures 14 and 15 are perspective views showing the construction in the case of a modified form of box.

Figure 16 is a perspective view showing that with the construction shown in Figures 14 and 15, upon the side walls being collapsed the end wall falls away.

Figure 17 is a cross section of a corner of the box showing a detail.

Referring to the drawings, the vertical side walls 1 and 2, bottom 3, lid 4, and flap 5, are made from one piece of cardboard. This sheet of cardboard, as shown in Figure 10, has cut-away V portions 6 along its sides at the folds of the walls of the box, such folds being indicated at 7 by dotted lines in Figures 9 and 10, so that a mitre, as at 8, will be formed when the sides of the box are folded into position. The parallel edges 9 on the sides of each projecting part 10 will meet in a butt joint, as clearly shown in Figures 5 and 6. Cleats 11 are attached to the bottom 3 and lid 4 on the parts 10 and secured by tacks 12. Half-cleats 14 are similarly secured by tacks 15 to the parts 10 of the vertical walls 1 and 2. After the cleats 11 and half-cleats 14 have been secured in position, they are then folded over to the position shown in Figure 9.

In Figures 13A, 13B and 13C are shown the stages in regard to the half-cleats 14, where "A" shows a half-cleat when it is first fastened to the cardboard. The first fold takes place along the dotted lines 16 and assumes the position shown in Figure 13B, from where it is turned up along the dotted line 17 to the position shown in Figure 13C. The cleats 11 on the bottom and lid are similarly folded over and would assume the position shown in Figure 12, but it will be noticed in regard to the half-cleats 14 on the sides 1 and 2 that a space 19 is left (see also Figure 6). The cleats 11 on the bottom and lid are formed with tenons 20, and the half-cleats 14 on the sides 1 and 2 are formed with open mortises 21. The end walls 22 of the box have half-cleats 23 attached to them at their vertical edges, these half-cleats being of a size corre-

sponding to the half-cleats 14, and secured by tacks 24 to the edge of the end 22 (as shown in Figures 2 and 3). These half-cleats 23 have open mortise ends 25 (see Figures 6 and 9) in the 5 same manner as the half-cleats 14.

Upon folding the vertical side walls 1 and 2 of the box into an assembled position, as in Figure 3, the tenons 29 of the cleats 11 will enter the open mortises 21 of the half-cleats 14. The 10 end walls 22 are now placed in position by entering the bottom ends of the half-cleats 23 into the space 19 between the half-cleats 14 and the vertical walls. The end may then be simply dropped or slid downwards as shown in Figure 3, 15 and when both end walls are inserted the box will assume the position shown in Figure 2. The lid 4 may now be closed, the tenons 29 of the cleats 11 on the lid entering the combined open mortises 21 and 25 in the top of the two half-cleats 14 and 23, and the box is brought finally 20 to the position shown in Figure 1, the flap 5 being tucked in on the inner side of the wall 1, as shown in Figure 4. An end frame is thus provided by means of the cleats, as shown in Figure 25 4, the corners of which are all securely locked together by the tenons and mortises. The construction of the corners of this frame is clearly shown in Figure 7, where it will be seen that the lower ends of the two vertical half-cleats will 30 be held by the tenon 28 of the horizontal cleat 11 passing through both of them. This locking of the cleats at the corners is a very important feature of this box. The joint of the flap with the walls can be sealed and made air-tight by 35 such means as wax, parchment paper, or the like.

The box may also be sealed by means of a sealing strip 40 (see Figure 17), consisting of 40 strong tough paper the full length of the box flap. This strip is provided with a gummed edge 41 which is adhered to the exterior of the edge of the side 1. It is then laid loose over the contents and when the flap 4 is inserted it will take the strip down with it and form a dust-proof joint. When the lid 4 is opened, the strip is simply lifted by the inside edge 42 and turned back, as indicated in dotted lines, and any dust held in the fold will be shaken out.

It will be seen by referring to the figures 50 especially to Figure 5, that since the ends of the cardboard sides have been folded around the cleats and half-cleats, the end walls 22 will butt against the folded-in edges of the cardboard at 55 27 and give a finished appearance to the box, completely obscuring the end frames.

The container may be easily opened while the 60 contents are still therein by opening the lid, sliding out the two end walls 22, and the two vertical side walls may then be collapsed, and the box again assumes the position shown in Figure 9.

Referring now to Figures 14 to 16, instead of the cleats being attached to the parts 10, the blank shown in Figure 10 would be cut without 65 these parts, as in the detail in Figure 11, and the cleats in this case would then be attached in the position indicated in the figure.

All the cleats on the walls are the same size in 70 this case, that is the bottom cleats 28 and the cleats 29 on the vertical wall are all the same section, but the tenons 30, however, are longer than the thickness of the cleat 29 by that of a cleat 32 on the end wall 33 (see Figure 15) so as to leave a space 31 between the cleat 29 and 75 the shoulder of the tenon 30 to receive mortised

end of the cleat 32 which, in the drawings, is shown half the thickness of the cleats 28 and 29. The cleats 32 are attached to the end walls 33 at a distance from the vertical edges of the wall corresponding to the width of the cleat 29 5 so that when the mortise 35 at the lower end of the half-cleat 32 engages with the tenon 30, the overhanging edge 34 will over-lap the cleat 29, as shown in Figure 14. The edge of the cardboard in this case covers only the outer sides 10 of the cleats as shown, and provides the mitre 8 but not the butt joint 9. This same form of blank may also be used with the construction described in reference to Figures 1 to 7, and 9 to 13. 15

An advantage of this construction is that upon the lid being opened, and the vertical walls being opened outwards, so that its cleats 29 will be clear of the tenons 30, the end walls 33, together with their cleat 32, and the bottom cleat 28 will 20 simply fall outwards, as indicated in Figure 16, without the necessity of actually drawing the end wall from engagement with the cleats.

The double cleats, instead of being on the vertical sides, may be arranged on the bottom 25 and top of the box, and in such a case the sides of the box hold up better while that is being fitted, and when the sides are collapsed, the ends become free.

As a further simplification, the cardboard 30 blank can be simply rectangular and the cleats attached to its edge, which in such a case would correspond to the dotted line 17 in Figure 10. Such a construction is indicated in Figure 8, 35 where the same reference letters are used as in Figures 14 to 16. In this case the cardboard is tacked to the cleats from the outer side as shown, and may be bound or strengthened with wires 26.

This construction also lends itself to a wooden box where the sides may consist of wood panels 40 bound by the wire 26 in the usual way. The ends 33 can also be of wood.

What I claim is:—

1. A collapsible container or box comprising 45 vertical side walls, horizontal walls forming the bottom and lid, end walls, said side and horizontal walls hingeably connected together, locking pieces on the walls in the form of cleats having tenons and open mortises, said cleats attached to the inner side of the horizontal and 50 vertical walls at the ends thereof, the tenons on one set of cleats entering the mortises of the cleat on the adjoining wall, and the tenons or mortises of the end wall cleats also engaging the tenons or mortises on the cleats of the horizontal 55 walls.

2. In the box as claimed in claim 1, an extended portion on the ends of the vertical and horizontal walls on which are secured the cleats, 60 said extended portion with the cleats thereon turned over, the cleats on the horizontal walls filling the space within the turned over part, the cleats on the vertical walls of lesser width and, therefore, leaving a space between its wall and the side of the lesser size cleat, the cleats on the 65 end walls of a size to enter such space when the container is assembled, the tenon or mortise of the end wall cleats, upon the box being assembled, engaging the tenon or mortise on the vertical and horizontal cleats projecting beyond the 70 cleats on such walls.

3. In the box as claimed in claim 1, the cleats attached to the end walls adapted to slide against that side of the cleats of the vertical walls remote from such walls and have their 75

tenons or mortises engaging the tenons or mortises of the cleats on the horizontal walls, on that side of such vertical cleats remote from the walls.

5 4. In the box as claimed in claim 1, the cleats attached to the end walls adapted to slide against that side of the cleats of the vertical walls remote from such walls and have their tenons or mortises engaging the tenons or mortises of the cleats on the horizontal walls, on that side of such vertical cleats remote from the walls, said cleats on the end walls attached at a position so that vertical ends of the end walls will project beyond them and overlap the interior side of the other wall cleats.

10 5. In the box as claimed in claim 1, the vertical side and horizontal walls formed of cardboard folded to form hingeable joints dividing the vertical side and horizontal walls, extended 20 portions on the ends of said walls, said cleats attached to the said extended portions which are folded over to partially envelop the said cleats.

15 6. In the box as claimed in claim 1, the walls formed of cardboard, an extended portion on the 25 ends of the vertical side and horizontal walls on which are secured the cleats, said extended portion with the cleats thereon to cover the cleats on three sides thereof folded over, the cleats on the horizontal walls filling the space within the 30 folded over part, the cleats on the vertical walls

in the form of half-cleats and, therefore, leaving a space between the wall and the side of the half-cleat, similar half-cleats on the end walls adapted to enter such space when the box is assembled, the tenon or mortise of the end wall half-cleats upon the box being assembled engaging the tenon or mortise on the vertical and horizontal cleats projecting beyond the half-cleats on such walls.

5 7. In the box as claimed in claim 1, the walls 10 formed of cardboard folded to form hingeable joints dividing the vertical side and horizontal walls, extended portions on the ends of the said walls, cleats attached to the said extended portions which are folded over to envelop the cleats 15 on two sides thereof, the tenons or mortises of the cleat on the horizontal walls being of a length so as to leave a space between the vertical cleats and the end of the tenon or mortise into which will fit the mortise or tenon on the ends 20 of the cleats on the end walls, so that when the vertical sides are collapsed the end wall and the cleat on the bottom horizontal wall will fall away.

25 8. In the box as claimed in claim 1, a paper closure strip adhered to the upper edge of a vertical side wall and lying loosely over the contents of the box, a flap on said lid adapted to push down said strip and form a dust-proof joint.

VICTOR ROY SCOTT. 30
